US00D973905S

(12) **United States Design Patent** (10) **Patent No.:** **US D973,905 S**
Verdier et al. (45) **Date of Patent:** **** Dec. 27, 2022**

(54) **SHED FOR BICYCLES**

(71) Applicant: **ALTINNOVA**, Bonson (FR)

(72) Inventors: **Corinne Verdier**,
Saint-Marcellin-en-Forez (FR); **Julien
Lefebvre**, Saint-Marcellin-en-Forez
(FR)

(**) Term: **15 Years**

(21) Appl. No.: **35/511,542**

(22) Filed: **Mar. 5, 2021**

(80) **Hague Agreement Data**

Int. Filing Date: **Mar. 5, 2021**

Int. Reg. No.: **DM/213031**

Int. Reg. Date: **Mar. 5, 2021**

Int. Reg. Pub. Date: **Mar. 19, 2021**

(51) **LOC (13) Cl.** **25-03**

(52) **U.S. Cl.**

USPC **D25/17**
